Hinkle. Atty.

UNITED STATES PATENT OFFICE

FRANK KITZELMAN, OF CHICAGO, ILLINOIS, ASSIGNOR TO ACORN WIRE & IRON WORKS,
OF CHICAGO, ILLINOIS, A CORPORATION OF ILLINOIS

GATE LOCK

Application filed October 13, 1930. Serial No. 488,310.

My invention relates to gate locks generally and more particularly to a gate lock for collapsible folding gates of the type commonly used to close off the corridors of banks, 5 office buildings and factory buildings and as protection for display windows, warehouses, garages and various other places.

In the folding gates in use at present locking means are ordinarily provided in the 10 form of a hasp secured to one gate post which extends through an opening in an adjacent gate post and a padlock is secured through the hasp to lock the doors together. These locks have not been altogether successful 15 due to the fact that persons desiring access to the enclosed premises simply saw the hasp and open the folding gates.

One of the objects of my invention is to provide an improved gate lock positioned 20 within the gate post so that unauthorized access is relatively difficult.

It is a further object of my invention to provide an improved gate lock of this type adapted to cooperate with the channel frame 25 members of one of the gate posts to securely lock the gates together.

A further object of my invention is the provision of an improved gate lock, the locking bolt of which is relatively inaccessible 30 by unauthorized persons.

Other advantages of my improved gate lock reside in the specific arrangement and construction of parts, further exemplified in the following description and illustrated in 35 the accompanying sheet of drawing, in which:

Fig. 1 is an elevational view of a corridor closed off by a typical folding gate provided with one of my improved locks;

40 Fig. 2 is an enlarged side elevational view of the upright end frame members with my improved lock attached thereto, the view being taken generally on the line 2—2 of Fig. 1 looking in the direction of the arrows;

45 Fig. 3 is a vertical sectional view through the locking means taken on the line 3—3 of Fig. 2;

Fig. 4 is a transverse sectional view taken on the line 4—4 of Fig. 1 and Fig. 2; and

50 Fig. 5 is a vertical sectional view on the

line 5—5 of Fig. 3 illustrating details of the lock construction.

In the drawing, in Fig. 1, 10 may indicate a corridor or passageway in a building having the foldable gates 12 extending across the passageway to close off the same. The gates 12 are preferably of a sheet metal construction comprising the back upright frame members 14 and the front upright frame members 16 supported upon the extensible 55 lazy tongs mechanism 18. Insofar as they have been described, the gates 12 may be of a standard construction such as is familiarly known to those skilled in the art.

The front upright frame members 16 may 60 each comprise a pair of channel shaped members 20 which have their side flanges directed inwardly. The members 20 are secured together in spaced relation by suitable rivets 22 which may also serve as pivots for the 65 ends of the extensible lazy tongs mechanism 18.

The gate lock of my invention may comprise a lock block 24 secured between the channel shaped members 20 of one of the 70 front upright frame members 16. The lock block 24 is formed in two parts 26 and 28, both of which have a portion 30 which extends over the exterior face of the upright 75 16 and a portion 32 formed to snugly fit against 80 the interior channel shaped wall of a member 20.

The lock block 24 may be securely fastened to one of the uprights 16 by means of rivets 34, which pass through suitable openings 36 85 in the upright frame members and suitable openings 38 in the lock block. Each of the half portions 26 and 28 of the lock block are provided with semi-cylindrical bores 42 to register, when the two parts are placed together to provide a suitable bore for a lock body 44 and a lock bolt 46. The lock bolt 46 is provided with a stud 51 to which the collar is rigidly attached by pressing, or it may be formed integral therewith. A key cylinder 90 46' which is integral with the stud 51 and the lock bolt 46, extends through the lock body 44 in the usual manner. A key slot is provided in the cylinder 46', which is adapted to receive a key which cooperates with the usual 95 100

tumblers of the lock. The construction is such that when the key is located in the slot it will allow the key to turn the cylinder 46', which being integral with the stud 51 and the lock bolt 46, will allow the turning of the T-shaped head 48. On the outer end of the lock body 44, a face plate 45 is provided which is pivoted by a rivet 47.

Means for holding the lock bolt in either a locking or unlocking position are provided and may comprise the collar 50 on the lock bolt which may be provided with a plurality of detent apertures 52. A pocket 54 is provided in the half block 26 and a detent finger 56 and compression spring 58 are positioned therein. The detent is so positioned with respect to the location of the T-portion 48 of the lock bolt that it will snap into a detent opening at vertical or horizontal positions of the head of the lock bolt 48, thus providing a useful function when the door is locked or unlocked as an operator will not be required to experiment with the door to discover whether the bolt is at the correct angle or at a slightly tilted angle.

It will be noted that the diameter of the lock bolt 46 and the width of the head 48 are slightly larger than the distance between the opposed flanges of the members 20. The frame member 16 in which the lock bolt is mounted is accordingly provided with arcuate grooves 60 through which the bolt 46 may pass and the other upright member 16 is formed with the elongated slots 62 through which the bolt member 48 may pass in its vertical position.

As may readily be understood from the drawing, the upright frame members 16 are drawn together as the gate is closed and the lock bolt head, being in a vertical position, will pass through the slotted opening 62 of the adjacent upright 16. By the insertion of a key into the lock cylinder 44 the lock bolt 46 and head 48 may be turned approximately ninety degrees, at which point the detent finger 56 will snap into a detent opening 52 and the lock bolt head 48 will be at right angles to the slotted opening 62 and the uprights 16 of the two portions of the extensible gate will be securely locked together. The bolt head 48 is formed with the bevelled edges 66 so that in the event of a slight mis-alignment of the uprights 16 the bolt head 48 will be guided into and through the slots 62.

While I have illustrated and described my invention as applied to extensible gates, it will be readily understood by those skilled in the art that numerous changes and modifications may readily be made without departing from the spirit of the invention, and I do not wish to be limited in any particular except as set forth in the claims, rather what I desire to secure and protect by Letters Patent of the United States is:

65 1. A gate lock for a folding gate having

a frame upright including a pair of spaced channel shaped members, comprising a split block secured in said frame upright between said members, a lock body secured within said block between said members, and a lock bolt adapted to be actuated by a key in said lock.

2. A gate lock for folding gates having a frame upright including a pair of spaced channel shaped members, comprising a split block assembled and securely attached to said frame upright between said channel shaped members, a lock body in said block, and a T-shaped lock bolt extending from said lock body and adapted to be actuated by a key.

3. A gate lock adapted for locking together a pair of extensible metal gates having upright frame members adapted to abut, each frame member including a pair of inwardly directed spaced channel shaped members, comprising a lock block secured in one of said upright frame members and having longitudinal grooves in which the said flanges of the channel members are received, and a lock bolt in said lock block extending from said frame member and adapted to engage the inner walls of the adjacent upright frame member to lock said gates together.

4. A gate lock adapted for locking together a pair of extensible metal gates having upright end frame members, each upright end frame member including a pair of spaced channel shaped members, comprising a split lock block secured in assembled condition within one of said frame members between said channel shaped members, a lock carried within said block so as to be non-removable therefrom and a T-shaped lock bolt in said lock extending from said frame member and arranged to engage the inner walls of the adjacent upright frame member to lock said gates together.

5. A gate lock adapted for locking together a pair of extensible gates having abutting vertical frame members, each frame member including a pair of channel shaped bars and means for securing said bars together in spaced relation and facing each other, comprising a lock carrying member secured between the channel shaped bars of one frame member adapted to engage the side flanges of said bars to prevent its removal from the assembled upright, a lock body in said carrying member, a lock cylinder carried in said body, and a lock bolt secured to said lock cylinder and extending to and engaging the inner sides of the side flanges of the adjacent frame member for locking said gates together in an extended position.

6. A gate lock adapted for locking together a pair of extensible gates having abutting vertical frame members, each frame member including a pair of channel shaped

bars and means for securing said bars together in spaced relation and facing each other, comprising a split lock carrying member secured between the channel shaped bars of one frame member and adapted to engage the side flanges of said bars to prevent its removal from the assembled upright, a lock body in said carrying member, a lock cylinder carried in said body, a lock bolt secured

10

to said lock cylinder and extending to and engaging the inner sides of the side flanges of the adjacent frame member for locking said gates together in an extended position, and means associated with said lock bolt for 70 yieldingly holding same in either a locked or an unlocked position.
